UNITED STATES PATENT OFFICE

HENRY B. OATLEY, OF GREAT NECK, NEW YORK, ASSIGNOR TO THE SUPERHEATER COMPANY, OF NEW YORK, N. Y.

SUPERHEATER

Application filed April 20, 1931. Serial No. 531,379.

My invention relates to fire-box superheaters and more particularly to superheaters installed in fire-boxes of locomotive type boilers equipped with so-called arch tubes.

5 The advantages of radiant type superheaters have been recognized insofar as economy of space and material are concerned, especially where a high degree of superheat is desired, but it has proven difficult to prevent the units of radiant type superheaters from burning out. These difficulties are particularly serious in a locomotive type boiler where the ordinary rate of combustion per unit volume is high.

10 15 It is an object of the present invention to provide a superheater having, at least in part, radiant type characteristics, and adapted for use in the combustion space of locomotive type boilers.

20 25 Further objects and advantages of my invention will be clear to those skilled in the art from the following description of a given embodiment of the invention taken in connection with the accompanying drawings in which:

Fig. 1 is a vertical central longitudinal section through a rear portion of an arch type fire-box in a locomotive type boiler.

30 Fig. 2 is a half-section of a boiler illustrated in Fig. 1, taken on the line 2—2 and looking in the direction of the arrows.

Fig. 3 is a transverse section of the boiler illustrated in Fig. 1, taken on the line 3—3 and looking in the direction of the arrows.

35 Fig. 4 is a view similar to Fig. 1 but illustrating a modified form of superheater in accordance with my invention.

Fig. 5 is a transverse half-section of a boiler illustrated in Fig. 4, taken on the line 5—5 and looking in the direction of the arrows.

40 45 A common form of construction in locomotive type boilers is one in which arch tubes are run from the water leg rearwardly and upwardly above the grates or burners and connected into the rear water leg. Ordinarily, arch brick are supported on the lower and forward portions of the arch tubes in such locomotives so as to form a baffle. In accordance with my invention, superheater

elements are run along the upper surface of the baffle formed by the arch bricks.

In Figs. 1, 2 and 3, I have illustrated a locomotive boiler 10 having smoke tubes 12, a forward water leg 14, and a rear water leg 16, respectively, as the front and rear ends of the fire-box 17. Extending rearwardly and upwardly between the water legs 14 and 16 and running above the grates or burners are arch tubes 18, 18. Extending across the fire-box 17 forward of the grate or burner space is a beam 20 above which is a fire wall 22, preferably of fire brick, and extending up to the plane of the arch tubes 18. The fuel is burned in the space 24 between the fire wall 22 and the rear face of the fire box in accordance with the common practice. On the arch tubes 18 are arch brick 26, 26 which may be of any usual or desired type. The fire wall 22 is spaced rearwardly from the forward water leg 14 enough to permit the insertion of the ends of superheater units between the wall and the water leg. In the arrangement shown, the means for leading steam to and from the superheater units comprises a header 28 which extends transversely of the boiler 10 just below the level of the beam 20 and between such beam and the water leg 14. Superheater units 30, 30 are connected to the header 28 and extend upwardly forward of the wall 22 and then rearwardly along the upper surface of the arch formed by the brick 26. Preferably the rear ends 32 of elements 30 are protected from the scouring action of the hot gases in the fire-box by special arch brick 34, 34, the upper ends 34a of which are curved forwardly above the rear upper ends 32 of the units 30. It will be seen that the units 30 not only receive heat by radiation from the combustion of gases in the combustion space above the arch but also receive a certain amount of heat by direct contact with the gases and that the undersurfaces of the 50 elements 30 receive heat by radiation directly through the fire brick 26. The heat absorption by units 30 is therefore quite high per unit area and the total area of these units can be small in proportion to the 100

80

75

85

90

95

amount of superheat added by them to the steam. However, to reduce the rate of depreciation of units 30, I prefer that they lie almost entirely below the level of the rear 5 upper end of the arch brick 26, whereby the convection heat flow to units 30 is kept low.

While the rate of heat absorption by the units 30 is high, in a great many cases it is not convenient to design the locomotive with 10 a long enough fire-box so that all the superheating surface can be placed above the arch. I have therefore illustrated in Fig. 1, besides the superheating surface in the units 30, additional superheater surface in 15 accordance with the Dalton Patent 1,031, 693. Such additional surface is furnished in the arrangement of Fig. 1 by units 36, 36 which also are shown as connected to the header 28, units 36 being placed in the combustion 20 space 38 and receiving heat primarily by contact with the gases passing to the tubes 12. In the arrangement illustrated in Fig. 1 having two groups of superheater elements at the rear of the tube sheet, I prefer to make the header 28 so that it can serve 25 both groups of elements 30 and 36. As illustrated, header 28 is connected by flanges 40, 40 to the mud ring 41 and to the beam 20 and has two internal webs 42 and 44 respectively which divide the header into three longitudinal chambers. The forward chamber of header 28 is indicated on the drawings by reference character 46, the central chamber by character 48 and the rear chamber 30 by character 50. Chamber 46 is connected through an inlet 52 and by a pipe, not shown, to the interior of the boiler. Steam which has been introduced into the chamber 46 passes thence into the units 36 and back 35 into the chamber 48. From the chamber 48 steam passes into the units 30 and then back into the chamber 50 from which it may be taken through an outlet 54 to the engine 40 throttle by a pipe, not shown. Preferably 45 the ends of the units 30 and 36 are clamped to seats in the top wall of header 28 by means of clamps 56, 56 and bolts 58, 58, bolts 58 extending down through the webs 42 and 44 below the lower face of the header 28 to 50 provide room for nuts 60, 60.

Arrangement shown in Figs. 4 and 5 is similar to that shown in Fig. 1 with the exception that the elements above the arch brick are arranged in a slightly different 55 manner. In the forms shown in Figs. 4 and 5, elements 30', 30' do not lie wholly in vertical planes, but are bent so that their heat absorbing portions lie in a plane parallel, or substantially parallel, to the surface 60 of the arch. They preferably are covered more or less by tiling 62 to prevent them from receiving heat by convection, the elements 30' having an entirely radiant type characteristic when completely covered by 65 tiling 62. However, when desired, a por-

tion of the tiling 62 may be removed to expose the upper surface of the elements 30', the tiling being formed in two parts 64 and 66 so that upper parts may be removed for this purpose. Uncovering elements 30' 70 by removal of some of the tile parts 66, however, does not greatly alter the radiant type heating characteristics of elements 30' since these elements lie so close against the upper surface of the arch that they are contacted only slightly by the gases. The upper and rearmost arch brick 34' in Figs. 4 and 5 are of slightly different shape from the brick 34 to permit the tile parts 66 to be placed over the free ends of units 30'. Similarly, the forward and lower brick 26a of the arch shown in Figs. 4 and 5 is specially shaped to hold the tiling 62 in place. 75

What I claim is:

1. The combination in a boiler fire-box 85 having arch tubes, of baffling on said tubes adapted to radiate heat from its upper surface and extending downwardly at the rear of the lower ends of said tubes, headers near the lower ends of said tubes, and superheater elements arranged along the upper and forward surface of said baffling and having end portions running down to and connected with said headers, said members all so arranged that said end portions lie 90 outside the current of combination gases. 95
2. The combination as set forth in claim 1 together with removable tiling over parts of the superheater elements. 100
3. The combination in a boiler fire-box 105 having arch tubes, of baffling means on said tubes, headers near the lower ends of said tubes and two sets of superheater units having connections with said headers, the units of one of said sets arranged forward of said headers and the units of the other of said sets arranged above said baffling means. 110
4. The combination as set forth in claim 1 and in which the heat absorbing portions of the superheater elements lie in parallel planes. 115
5. The combination as set forth in claim 1 and in which the superheater elements are bent so that the heat absorbing portions lie in the same plane. 120
6. The combination as set forth in claim 1 and in which the superheater elements are bent so that their heat absorbing portions lie in a plane substantially parallel to the baffling on the arch tubes. 125
7. The combination as set forth in claim 1 together with a fire wall in the forward portion of the fire-box extending up to the level of the arch tubes at the forward end of the baffling and lying closely adjacent the headers. 130
8. The combination as set forth in claim 1 and in which the major portion of the surface of the superheater elements lie be-

low the level of the upper rear end of the baffle.

9. The combination in a boiler fire box having arch tubes, of baffling on said tubes, superheater elements arranged along the upper surface of said baffling, and headers for said elements near the lower ends of said tubes to which the elements are connected, said baffling having non-metallic means separate from said elements and arranged to protect the rear upper ends of said elements from direct impact of gases.

10. The combination in a boiler fire box having arch tubes, of baffling on said tubes adapted to radiate heat from its upper surface, superheater elements arranged along the upper surface of said baffling, headers for said elements near the lower ends of said tubes and to which the elements are connected, said baffling having refractory means at its rear upper end adapted to protect the rear ends of said elements from direct impact of gases and having means at its lower end adapted to support the longitudinal thrust of tiling carried on its upper surface.

CERTIFICATE OF CORRECTION.

Patent No. 1,905,739.

April 25, 1933.

HENRY B. OATLEY.

It is hereby certified that error appears in the printed specification of the above numbered patent requiring correction as follows: Page 2, line 96, claim 1, for "combination" read combustion; and that the said Letters Patent should be read with this correction therein that the same may conform to the record of the case in the Patent Office.

Signed and sealed this 8th day of January, A. D. 1935.
